Dec. 1177

Garrettson Smith & Henry Brown, of Philadelphia, Pa.
Assignors to James G. Abbott, of same place.
Letters Patent No. 1177, dated Dec. 20, 1839.

The schedule referred to in these Letters Patent and making part of the same.

To all whom it may concern:

Be it known that we, Garrettson Smith and Henry Brown, both of City and County of Philadelphia, and State of Pennsylvania, have invented or produced a new and original design for a parlor stove, termed the "Violet" and we do hereby declare the following to be a full clear and exact description of the same, reference being had to the accompanying drawing in which

Fig: 1. is a front view of the stove.

Fig: 2. a plan of the top plate.

Fig: 3. a plan of the base, and

Fig: 4. a full sized sectional view of the moulding on the edge of the lower plate A.

The base is the form shown in the drawing, the edge of the lower plate A. being ornamented in bas relief with flutes, and near the ash pit, with sprigs and leaves as seen in Fig: 3.

Upon the rising portion of the base are foliated sprigs, seen in Fig: 1. and the upper plate is edged with a moulding with sprigs at intervals, and round the ring for receiving the cylinder, with a fluted moulding, as seen in the drawing.

The top plate B. of the stove, is edged with a moulding ornamented with sprigs and egg shaped indentations.

Underneath this moulding is a fluted moulding, round the cylinder and flue pipes, and on the top of the plate are two ornamental crosses C. & D. and E. as well as an ornamental circular raised portion F. which forms the base of the ornamental iron E.

Dec 1177

The door frame H, is ornamented with beams and friezes as shown in the drawing, and forms an ornamental door.

Mc Bain.

The design and configuration of the ornamental drawings, as above described and set forth in the annexed drawing, and as forming the sides of a parlor stove.

In testimony whereof, we have signed our names to
this Specification, in the presence of the following witnesses,

Exd. Witnesses.
